[57] CLAIM

The ornamental design of a filter regulator unit, as shown and described.

DESCRIPTION

FIG. 1 is a front perspective view of a filter regulator unit showing our new design;

FIG. 2 is a front elevational view thereof;

FIG. 3 is a back elevational view thereof opposite to that shown in FIG. 2;

FIG. 4 is a side elevational view thereof, the opposite side being a mirror image thereof;

FIG. 5 is a top plan view thereof; and,

FIG. 6 is a bottom plan view thereof.
